UNITED STATES PATENT OFFICE.

IDA M. FINCH, OF CHICAGO, ILLINOIS.

ABDOMINAL SUPPORT.

1,139,656.

Specification of Letters Patent. Patented May 18, 1915.

Application filed April 10, 1913. Serial No. 760,148.

To all whom it may concern:

Be it known that I, Ida M. FINCH, a citizen of the United States, residing at Chicago, Cook county, Illinois, have invented 5 certain new and useful Improvements in Abdominal Supports, of which the following, taken in connection with the drawing, is a description.

My invention has for its object the production of an abdominal supporter, which is adapted to be used as a supporter and a truss, or either, and to provide such a device which shall be much improved in construction and efficiency.

15 My device is adapted to adjust itself to the body of the wearer and to be maintained in position without the use of hose supporters or other straps which exert a downward pull in an attempt to hold the supporter in proper position on the body.

20 With the above and other objects and advantages of construction in view, my invention consists of certain details and arrangement of parts hereinafter described and 25 shown in the drawings, in which—

Figure 1 is a perspective view of my supporter; Fig. 2 is an inside view of the device looking from the bottom toward the top; Fig. 3 is a detail illustrating the adjustable pad.

Referring to the drawing A represents the body of the supporter which may be of any material suitable for the purpose. This device is constructed and arranged to 35 be laced at the back as shown at A', the back of the supporter preferably extending a short distance above the waist line, although in some instances the back extends only to the waist line of the wearer. Upon 40 either side of the lacing A' are vertically arranged steels or whalebones a, a, which extend from the top to the bottom of the supporter. Upon either side of the stays a, a, and extending from the top to the 45 bottom of the support is a single stay a', a'. The stays a', a' extend from the waist line forwardly and downwardly to the bottom of the supporter. The stays a, a, and a', a' are the only stays in the support, and by 50 means of the construction and arrangement as herein described I am enabled to maintain the device perfectly in shape upon the body without the tendency to wrinkle or move upwardly toward the waist line.

55 B is a strip of webbing extending from the top to the bottom of the support at the

center front. Upon each side of the webbing B is a webbing strip B', B', each of which extends from the waist line downwardly and backwardly to the bottom edge 60 of the flaps C, C'. Upon each side of the front center webbing B is a reinforcing flap C, C'. Each of these reinforcing flaps is practically triangular in shape with the lower corner thereof detached from the 65 body portion, and being provided at the free corner thereof with a fastening device which may be a buckle e, or any other well known securing means. One edge of each of these flaps is secured with the center 70 webbing B to the body of the support. A strip of webbing D encircles the supporter at the waist line and terminates at the back with a buckle or other fastening device d. Extending across the front of the 75 supporter at the bottom thereof is a strip of webbing D' which extends to the ends of the reinforcing flaps C, C' and is provided with the fastening devices d', d'. Strips of webbing e, e' extend around the 80 bottom edge of the supporter to the back thereof where they are secured together with a buckle or other fastener E. Each of these strips extend forwardly to a point where they are met by the fastening devices upon the ends of the reinforcing 85 strips C, C', and are secured together. I contemplate using several of these laterally extending strips of webbing when greater compression across the abdomen is desired. 90 These strips e, e' and D' are capable of adjustment to permit of more or less lateral compression across the abdomen as desired.

F is a pad of any size or shape desired, which is adapted to be secured in position 95 where required by simply attaching it to the body of the supporter with any removable fastening device, as for instance a safety pin, f.

It will be observed that I have provided 100 a central vertical support at the back, which extends above the waist line. The angularly extending supports a', a', follow the lines of the muscles of the body in supporting each side of the back. With the 105 back of the wearer thus reinforced along the natural lines of traction, the abdomen may be supported by such compression as may be provided by adjusting the lacing at the back, and by the circumferentially 110 extending webbing strips e, e' and D. When the pad F is attached in the position

desired by the fastening of the compression thereon when the support is secured in place is sufficient to maintain it.

I claim:—

- 5 An abdominal supporter formed of a piece of material adapted to encircle the body below the waist line, vertical stays at the center back of the support, a single stay upon each side of the center back 10 which extends from the waist line forwardly and downwardly to the bottom of the same, triangular shaped reinforcing flaps secured from the waist line to the bottom at the center front of the support,

the backwardly extending corners thereof 15 being free, means secured to the body of the supporter for engaging the free ends of the reinforcing strips to provide lateral compression around the body, and a detachable pad secured inside said support, substantially as described.

In testimony whereof I have signed this specification in the presence of two subscribing witnesses.

IDA M. FINCH.
